UNITED STATES PATENT OFFICE.

BERNARD MEYER, OF PHILADELPHIA, PENNSYLVANIA.

BAKE-OVEN.

SPECIFICATION forming part of Letters Patent No. 783,215, dated February 21, 1905.

Application filed June 11, 1904. Serial No. 212,103.

To all whom it may concern:

Be it known that I, BERNARD MEYER, a citizen of the United States, residing in the city and county of Philadelphia, State of Pennsylvania, have invented a new and useful Improvement in Bake-Ovens, of which the following is a specification.

My invention consists of a bake-oven in which provision is made for heating the floor, 10 the roof or arch, the interior of the baking-chamber, and both sides of said chamber, provision being also made for cutting off certain courses of heating when so desired, as will be hereinafter described, the novel features being pointed out in the claims.

Figure 1 represents a vertical section of a bake-oven embodying my invention on line *x x*, Fig. 2. Fig. 2 represents a partial plan view and partial horizontal section thereof. 20 Fig. 3 represents a vertical section on line *y y*, Fig. 1. Fig. 4 represents a vertical section on line *z z*, Fig. 1. Fig. 5 represents a horizontal section on line *a a*, Fig. 1.

Similar letters of reference indicate corresponding parts in the figures.

Referring to the drawings, A designates the body of the oven, and B the furnace thereof. C designates the hearth of the oven, between which and the floor D of the baking-chamber 30 E is the flue F, the upper wall or ceiling of which is composed of a series of arches, whereby the products of combustion or heat admitted into said flue F impinges successively against the several scallops or arches, thus effectually heating the same, the effect of which is communicated to the floor of the chamber E, it being seen that the furnace B is in communication with said flue F, as most clearly shown in Fig. 1.

40 G designates a vertically-extending tube which passes through the floor of the oven and communicates with the flue F, said tube being connected with the pipe H, which is located in the chamber E, and passes around one side of the oven, the back, and the other side thereof, and its terminal J is in communication with the chimney or stack K.

At one end of the body, in the present case the left-hand end thereof, is the vertical flue 45 L, whose lower end is in communication with

the rear of the flue F, the upper end of which is in communication with the horizontally-extending flue M, which passes diagonally over the arch or roof of the chamber E and has its terminal connected with the pipe P, the latter opening into the flue or stack K, it being noticed that one end of a horizontally-extending flue Q opens into said pipe P, said flue Q and pipe being in the right-hand side of the body, it being noticed that one end of said flue Q is connected with the vertical flue R, the lower end of the latter being in communication with the flue F, whereby the products of combustion from the latter may be admitted into the flues R and Q, it being noticed that the flue Q at its terminal communicates with the flue P, and thus is in communication with the chimney or stack K. Connected with the terminal of the flue M is the damper S, and connected with the flue P is 65 the damper T.

The operation is as follows: The products of combustion leave the furnace B and enter the flue F in the direction of the arrows 1, thus heating the ceiling or roof of said flue, the effect of which is transmitted to the floor of the chamber E, whereby said floor is in a highly-heated condition. The products of combustion enter the pipe H and traverse the same along one side of the chamber E, the back, and the other side thereof within the chamber E, as indicated by the arrows 2, thus effectively heating said chamber, the products of combustion then entering the chimney or stack K. Should it be desired to heat, say, 75 the left-hand side of the chamber E, the damper S is opened, whereby the products of combustion rise in the flue L, and thus heat the adjacent portion of the body A, (see arrows 3,) the products of combustion then entering 80 the pipe M, which passes over the roof or arch of the chamber E, (see arrows 4,) thus heating said roof or arch, the effect of which is communicated to the top or upper portion of said chamber. When the products of combustion leave the flue M, they enter the flue P, and so reach the chimney or stack, the damper T having also been opened. Should it be desired to heat the right-hand side of the chamber E, the damper S may be closed, where- 85 90 95 100

by some of the products of combustion enter the flues R and Q, as shown by the arrows 5 and 6, thus heating the corresponding portion of the body A, the products of combustion 5 then reaching the chimney or stack through the flue P, (see arrow 7,) the flues M and Q being confluent at the flue P. If desired, both dampers S and T may be opened, whereby the products of combustion entering 10 the flues M and Q are confluent at the flue P, and so reach the chimney or stack, as per arrow 7, it being evident that by these means an oven may be effectively heated from within, from below, above, and at its opposite 15 sides all at one time, or some of the courses may be cut off, this being accomplished by suitably opening and closing the relative dampers.

Various changes may be made in the details 20 of construction shown without departing from the general spirit of my invention, and I do not, therefore, desire to be limited in each case to the same.

Having thus described my invention, what 25 I claim as new, and desire to secure by Letters Patent, is—

1. An oven having a flue leading from the furnace below the floor of the baking-chamber, vertical flues common to said furnace-flue 30 at opposite corners thereof, a pipe extending from one of said vertical flues around the sides and back of the oven within said baking-chamber, a top flue above the roof of the baking-chamber communicating with the other vertical flue, an exit-pipe with which said top flue is in communication, an auxiliary vertical flue leading from the furnace-flue and a horizontally-extending flue extending from said auxiliary vertical flue and being confluent with 35 40 said exit-pipe.

2. An oven having a flue leading from the furnace below the floor of the baking-chamber, vertical flues common to said furnace-flue at opposite corners thereof, a pipe extending 45 from one of said vertical flues around the sides and back of the oven within said baking-cham-

ber, a top horizontal flue above the roof of the baking-chamber communicating with the other vertical flue, an exit-pipe with which said top flue is in communication, an auxiliary vertically-extending flue leading from the furnace-flue, a horizontally-extending flue extending from the auxiliary vertical flue and being confluent with said exit-pipe and dampers in different members of the confluent flue 55 and pipe.

3. An oven having a flue leading from the furnace below the floor of the baking-chamber, vertical flues common to said furnace-flue at opposite ends thereof, a pipe extending from 60 one of said vertical flues around the sides and back of the oven within said baking-chamber, a flue above the roof of the said chamber communicating with the other vertical flue and extending diagonally therefrom, an exit-pipe with which the diagonal flue is in communication, an auxiliary vertically-extending flue leading from the furnace-flue, and a horizontally-extending flue extending from said auxiliary vertical flue and being confluent with 65 70 said exit-pipe.

4. An oven having a flue leading from the furnace below the floor of the baking-chamber, vertical flues common to said furnace-flue at opposite ends thereof, a pipe extending from 75 one of said vertical flues around the sides and back of the oven within said baking-chamber, a horizontal flue above the roof of the said chamber communicating with the other vertical flue and extending diagonally therefrom, an exit-pipe with which the diagonal flue is in communication, an auxiliary vertically-extending flue leading from the furnace-flue, a horizontally-extending flue extending from 80 85 said auxiliary vertical flue and being confluent with said exit-pipe, and dampers in different members of the confluent flue and pipe.

BERNARD MEYER.
